UNITED STATES PATENT OFFICE.

ALBERT ROTZELL, OF STROUDSBURG, PENNSYLVANIA.

LATCH.

Application filed May 28, 1924. Serial No. 716,419.

To all whom it may concern:

Be it known that I, ALBERT ROTZELL, a citizen of the United States, residing at Stroudsburg, in the county of Monroe and 5 State of Pennsylvania, have invented new and useful Improvements in Latches, of which the following is a specification.

This invention relates to latches.

The object is to provide a latch which 10 may be readily stamped from sheet metal, and is especially adapted for use in connection with trunks, suit cases, chests, lunch boxes, and other containers, the present application being a companion application to 15 one filed by me of even date herewith for a patent on a lunch box.

Another object is to provide a strong and durable and cheaply manufactured device 20 of this character, composed of few parts, which may be readily installed in position on the members to be connected together, and which may, by a simple manipulation, be caused to be fastened together without danger of becoming accidentally unfastened, and just as easily unfastened to permit 25 access to the container.

A full and complete understanding of the invention may be obtained from a consideration of the following detailed description 30 taken in connection with the accompanying drawing forming a part of this specification, it being understood that while the drawing shows a practical form of the invention, the latter is not to be confined to strict conformity with the showing thereof, but may 35 be changed or modified, so long as such changes or modifications mark no material departure from the salient features of the invention, as specifically pointed out in the 40 appended claims.

In the drawing, in which similar reference characters designate corresponding parts throughout the several figures:

Figure 1 is a perspective view of the improved latch in engaged position;

Figure 2 is a vertical, longitudinal sectional view through the same, the coacting members being latched together;

Figure 3 is a view similar to Figure 2, the 50 parts being unlatched;

Figure 4 is an enlarged transverse sectional view taken on the line 4—4 of Figure 2, and looking in the direction of the arrows;

Figure 5 is a similar view taken on the

line 5—5 of Figure 2 and looking in the direction of the arrows;

Figure 6 is a detail perspective view of the keeper frame;

Figure 7 is a similar view of the sliding keeper;

Figure 8 is a detail perspective of the swinging latch detached from its attaching plate.

The invention consists of two coacting members or parts, one member or part carrying a swinging latch, which is preferably attached to the body of a trunk, case, chest or box, while the other member or part embodying means for coaction with the said 70 latch and having a sliding keeper, is preferably attached to the cover or closure of said container, though it is to be understood that the positions of the two coacting members 75 may be reversed.

The second-named member or part comprises what may be termed a keeper frame formed of a single strip of suitable sheet metal, such as brass, which may be nickel-plated or otherwise treated to withstand 80 wear and exposure. The said keeper frame includes a base plate 1 having the terminal portions of the strip constituting the same returned thereupon, as at 2, to provide relatively heavy, strong and durable attaching 85 ears, which are suitably apertured for the reception of rivets 3, or other fasteners, for rigidly holding the frame to the front face of the cover or lid, as before stated.

The terminals of the sheet of metal are 90 directed towards each other and are bent outwardly at an angle to provide spaced, dove-tailed guides 4 extending from top to bottom of the base plate and equi-distant from the vertical center thereof.

The base plate is provided at its top edge with an integral, outstanding stop flange 5, which overlaps the upper ends of the guides and has its end edges bevelled to conform to the shape of said guides. The lower edge of 100 the base plate is likewise provided with an integral, outstanding locking flange 6, which is elevated somewhat above the lower ends of the guides and has its ends spaced from the same to provide passageways, for a 105 purpose to be explained.

A sliding keeper is mounted for up and down sliding movement within the guides 4, and comprises a plate 7 extending from the inner edge of one guide to the opposite inner 110

edge of the other guide, the vertical edges of said plate being provided with integral wings 8 bent at an angle to conform to the shape of said guides and fitting beneath the 5 same, and extending to a point adjacent to the base plate, so that the keeper may be freely moved up or down and is prevented from dislodgement from between the guides.

The plate 7 extends somewhat above the 10 upper ends of the wings and is bent outwardly and thence inwardly upon itself to form a finger piece 9, the terminal being projected inwardly beyond the inner face of the plate to form an abutment flange 10, 15 which lies at all times above the aforesaid stop flange 5, and is adapted, when the sliding keeper is lowered, to abut against the same and support said keeper at the proper elevation. When the abutment 10 is resting on the flange 5, the lower edge of the plate 7 is located below the locking flange 6, and the side wings 8 occupy the passageways at either end of said flange 6, and when the said keeper is elevated by means of the 20 finger piece 9, the lower edge of said plate 7 uncovers the said flange 6, and the upward movement is arrested by the upper ends of the wings 8 abutting against the under face of the stop flange 5, as clearly shown in 25 Figure 3 of the drawing.

An attaching plate 11, preferably of some ornamental design is suitably apertured for the reception of rivets 12 for fastening the same to the other member of the container 30 on which the latch is to be used, and said plate 11 is provided at its upper edge with suitable hinge eyes 13 between which the complementary hinge element 14 of a swinging latch member 15 is pivoted by a pin 16, 35 thus permitting the swinging latch to be swung up or down.

The swinging latch member comprises a plate extending parallel to the hinge members and having its ends bent outwardly and 40 directed towards each other to form clamps 17, which securely clamp the terminal foot portions of a bowed handle 18, extending outwardly from the latch, and adapted to be grasped by the fingers to swing the said 45 latch up or down. The upper edge of the latch plate 15 is provided with an upwardly and outwardly extending tongue 19, which terminates in an inwardly directed lip 20 and the parts are so associated and secured 50 in position as to cause the said lip 20 to engage over the aforesaid locking flange 6 when the latch is swung upwardly as shown in Figure 2. In order to permit of such engagement, however, the sliding keeper 7 must be elevated, as shown in Figure 3, when the lower edge of the plate 7 is sufficiently above the flange 6 as to permit the 55 lip 20 to be so engaged, after which the keeper plate 7 is lowered until the abutment 60 10 strikes the stop flange 5, when the down-

ward movement is arrested. In this position, the lower edge of the keeper prevents the outward swinging movement of the latch which is thus held in its engagement with the flange 6.

From the foregoing it will be seen that a simple, cheaply manufactured, and easily operated device has been provided for use as a latching means on trunks, and for general purposes, the same having few parts to become broken or deranged, and the entire device may be formed by simple stamping process from sheet metal, and bent and formed into shape to accomplish the desired result.

What is claimed is:—

1. A latch comprising a keeper frame adapted to be attached to an element, said frame comprising spaced, substantially vertical, inclined guide flanges, a lower locking flange extending horizontally between the guide flanges and having its ends spaced therefrom, a sliding keeper plate mounted between the guides and having side wings adapted to slide beneath the guides to prevent dislodgment of the keeper and to straddle the locking flange, and a latch member hinged to the other element and having a lip to engage the locking flange and being held thereto when the keeper is slid downwardly to cover the latch.

2. A device of the class described comprising two coacting members adapted to be attached respectively to two parts to be fastened together, one of said coacting members comprising a longitudinal guideway, a slidable keeper mounted in the guideway, means for holding the keeper in the guideway, means for limiting the sliding movement of the same, a transverse outstanding locking flange located within the guideway, the other coacting member comprising an attaching plate, a swinging latch hinged thereto and having an inturned lip adapted to hook over the said locking flange when the latch is swung, said lip and flange being held in engagement when the keeper has been moved into covering relation thereto.

3. A latch comprising a keeper frame having means for attachment to one member, a central guideway, a transverse, outstanding locking flange located at one end of the guideway, a transverse stop flange located at the other end thereof, a slidable keeper having marginal wings mounted in the guideway, said keeper having a transverse, inwardly projecting abutment adapted to engage the said stop flange when moved in one direction, and a swinging latch hinged to the other member and having a lip for engagement with the locking flange and adapted to be held thereto by the keeper when the same is lowered.

4. A latch comprising a keeper frame formed with attaching ears at each end

thereof and having centrally disposed, spaced, dove-tailed guides, a transverse outstanding locking flange formed on the base of the frame between the guides and adjacent to one end thereof, a transverse stop flange formed on said frame at the other end of the guides, a sliding keeper having inclined side wings mounted within the guides, said wings being shorter than the guides and adapted to strike the stop flange to limit the sliding movement of the keeper in one direction, and a hinged latch having a lip and adapted to be swung to engage with the said locking flange and to be held thereto by the keeper when the same is in covering relation.

5. A latch comprising a keeper frame adapted to be attached to an element, said frame comprising spaced, vertical, inclined 20 guide flanges, a horizontal stop flange joining the upper ends of the guides, a lower locking flange extending horizontally be-

tween the guides and having its ends spaced therefrom, a sliding keeper plate mounted between the guides and having side wings adapted to slide beneath the guides to prevent dislodgment of the keeper and to straddle the locking flange, said plate also having a rearwardly extending abutment flange adapted to strike the stop flange when the lower end of the keeper is over the latter to prevent further downward movement, the upper ends of said wings contacting with the stop flange to limit the upward movement of the keeper, and a latch member 35 hinged to the other element and having a lip to engage the locking flange and held thereto when the keeper is slid downwardly to cover the latch.

In testimony, that I claim the foregoing as my own, I have hereto affixed my signature.

ALBERT ROTZELL.
